No. 694,796.

F. A. SICKLESTEEL.
SECTIONAL CULVERT.
(Application filed May 31, 1901.)

Patented Mar. 4, 1902.

(No Model.)

UNITED STATES PATENT OFFICE.

FRANK ABRAM SICKLESTEEL, OF NORTHBRANCH, MICHIGAN.

SECTIONAL CULVERT.

SPECIFICATION forming part of Letters Patent No. 694,796, dated March 4, 1902.

Application filed May 31, 1901. Serial No. 62,520. (No model.)

To all whom it may concern:

Be it known that I, FRANK ABRAM SICKLESTEEL, a citizen of the United States, and a resident of Northbranch, in the county of La-
5 peer and State of Michigan, have invented a new and Improved Sectional Culvert, of which the following is a full, clear, and exact description.

The object of the invention is to provide a
10 new and improved sectional culvert designed for use on highways, railways, and the like and arranged for convenient setting up or forming in a trench without the aid of skilled labor and constructed to give the greatest
15 strength for height and capacity and not liable to be damaged by frost or ice.

The invention consists of novel features and parts and combinations of the same, as will be fully described hereinafter and then
20 pointed out in the claims.

A practical embodiment of my improvement is represented in the accompanying drawings, forming a part of this specification, in which similar characters of reference indicate corresponding parts in all the views.

Figure 1 is a side elevation of the improvement with a side section removed. Fig. 2 is a cross-section of the same. Fig. 3 is a plan view of the same, and Fig. 4 is an end view
30 of a modified form of the improvement.

The improved sectional culvert illustrated in Figs. 1, 2, and 3 consists, essentially, of a base A and sectional arched sides B B', made of suitable material, their upper or apex ends
35 abutting, as is plainly indicated in Fig. 2. The lower ends of the sections B B' are made V-shaped to be seated in correspondingly-shaped longitudinal seats A', formed on the top face of the base A near the sides thereof,
40 so that the sections B B' are not liable to slip out of position after the earth is filled into the trench containing the culvert. The sections B B' are made of suitable length and are arranged to break joints at the ends, as
45 is plainly indicated in Fig. 3, and said sections are formed at their upper or apex ends with spaced lips B², of which the lips of one section interlock with the lips on the opposite section, so that the sections B B' are held
50 against longitudinal movement, but are free to open up outwardly in case ice forms in the culvert and presses the sections outward against the surrounding filled-in ground. Thus the sections B B' are not liable to be
55 broken by the expansion of freezing water,

and when the ice melts the weight of the surrounding ground forces the sections B B' back into a firm interlocked position.

The base A may be made of a single piece, as shown in Figs. 1, 2, and 3, or two pieces A², as shown in Fig. 4; but each piece is formed with a longitudinal seat A' for receiving the lower end of the corresponding section B or B'. The base-pieces A² are set on suitable abutments C, it being understood
60 that this construction of the culvert is more especially designed for use on small streams, creeks, and the like.

By arching the side sections B B', as shown, and having their apex ends abutting, as described, it is evident that the greatest strength
65 for height and capacity of the culvert is obtained.

I do not limit myself to any particular material for forming the base and sides, and it
70 is also evident that the culvert-sections may be constructed before setting up in a trench or they may be formed in the trench.

Having thus fully described my invention, I claim as new and desire to secure by Letters
75 Patent—

1. A sectional culvert, comprising a base, oppositely-disposed side sections mounted upon the same and arranged to break joints with each other, said side sections being provided with serrated edges for forming a
80 structure.

2. A sectional culvert, comprising a base, oppositely-disposed side sections mounted upon the same and arranged to break joints with each other, each section having the general shape of a semi-arch and being provided with a serrated edge having alternately-disposed bevels for the purpose of locking said edge to similar edges on other sections.
85

3. A sectional culvert, comprising a base, oppositely-disposed side sections each having the general shape of a semi-arch, and mounted upon said base so as to engage opposite side sections at the top, the upper edges of the sections being provided with serrations and slightly rounded externally, thereby forming a rotund, smooth external apex.
95

In testimony whereof I have signed my name to this specification in the presence of
100 two subscribing witnesses.

FRANK ABRAM SICKLESTEEL.
